UNITED STATES PATENT OFFICE

2,072,715

MEANS FOR OBLIVIATING WATER HAMMER
IN SERVICE PIPESGeorge Jessop, Ingle Nook, Gomersal, near Leeds,
EnglandApplication March 16, 1936, Serial No. 69,150
In Great Britain March 22, 1935

1 Claim. (Cl. 137—104)

This invention relates to improved means for obviating water hammer in service pipes. As is well known, the cause of "water hammer" is primarily due to excessive pressure in the water supply. When a cock or tap controlling the discharge of cold water from a pipe feeding a cistern, the supply to which is effected by a ball cock, is closed, the impulse imparted to the water is transmitted by the pressure to the ball cock lever through the ball cock valve. The movement of the ball starts ripples on the surface of the water in the cistern. This movement causes the valve to be continually sipping water from the supply, thereby obtaining force from the high pressure supply to ensure the completion of this cycle. The primary object of this invention is to overcome this drawback in a simple and reliable manner.

The present invention comprises means for damping out the oscillations of the ball cock lever.

A convenient means for effecting the object in view, comprises a baffle plate consisting of a disc provided with an upstanding boss to form an air chamber on its underside suspended from the ball float or its lever by suitable means so that the baffle plate or its equivalent is always submerged.

This invention will be now more particularly described making reference to the accompanying drawing in which:—

Fig. 1 is a view in sectional side elevation of a cistern, supplied with cold water through a ball cock valve, fitted with the present invention.

Fig. 2 is a view in plan thereof.

Fig. 3 is a broken view in side elevation of a modification.

Figs. 4 and 5 are views in side elevation and plan respectively of a modified form of baffle plate.

Throughout the views similar parts are marked with like figures of reference.

A cistern 1 is fed with cold water 2 from a service pipe 3 through a valve 4. The valve 4 is opened and closed by means of a lever 5 operated by the ball float 6. The outlet for the water

from the cistern is by means of a pipe 7. So far, all these parts are of well known construction. A baffle plate 8, which may consist of a thin flat disc, as shown in Figs. 1-3, preferably of aluminium or other relatively light weight material, is attached at its centre to the one end of a flexible connecting means, such as a chain 9, the other end of which is attached to the lever 5. The length of the chain 9 and the limits of movement of the lever 5 are in such relation that the baffle plate 8 is always submerged in the water 2 and well below any level it may assume.

The chain 9 is preferably attached to the lever 5 as near the ball float 6 as is practicable, as shown in Figs. 1 and 2.

In a further modification, the baffle plate 8 may be attached directly to the ball float 6 and in order to readily adapt the invention to existing cisterns, the baffle plate 8, see Fig. 3, may be attached to the ball float 6 by means of a clip 10, for instance a three pronged clip embracing the ball float 6 as shown.

The baffle plate 8 instead of being a flat disc, is preferably dished or domed, or may be formed with a centrally arranged upstanding boss 11, see Figs. 4 and 5, forming a small air chamber or cavity 12 on its underside. As the baffle plate or its equivalent is always submerged, and since the ripple produced on the water within the cistern is purely a surface ripple, it does not communicate any motion to the baffle plate, which thereby controls or prevents an oscillatory movement of the ball cock lever.

I declare that what I claim and desire to secure by Letters Patent is:—

Means for obviating water hammer in service pipes supplying cold water to a cistern by means of a ball cock, comprising in combination a disc of relatively light weight material, an upstanding boss in said disc to form an air chamber on its underside, and a chain attached by its one end to the disc and at its other end to the ball cock lever near the ball, the said chain being of such a length as to ensure that the disc is always below the level of the water in the cistern, as set forth.

GEORGE JESSOP.
